US00D997915S

(12) **United States Design Patent** (10) **Patent No.:** **US D997,915 S**
(45) **Date of Patent:** **** Sep. 5, 2023**

(54) **REMOTE CONTROL**

(71) Applicant: **Zhejiang Kangbeide Smart Furnishings Co., Ltd.**, Zhejiang (CN)

(72) Inventor: **Yuelian Xu**, Zhejiang (CN)

(73) Assignee: **Zhejiang Kangbeide Smart Furnishings Co., Ltd.**, Zhejiang (CN)

(**) Term: **15 Years**

(21) Appl. No.: **29/811,540**

(22) Filed: **Oct. 15, 2021**

(51) **LOC (14) Cl.** **14-03**

(52) **U.S. Cl.**

USPC **D14/218**

(58) **Field of Classification Search**

USPC D14/218, 217, 356, 358, 496; D13/162, D13/162.1, 168; D10/49

(57) **CLAIM**

The ornamental design for a remote control, as shown.

DESCRIPTION

FIG. 1 is a perspective view of a remote control showing a first embodiment of my new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a perspective view of a remote control showing a second embodiment of my new design;
FIG. 10 is another perspective view thereof;
FIG. 11 is a front view thereof;
FIG. 12 is a rear view thereof;
FIG. 13 is a left side view thereof;
FIG. 14 is a right side view thereof;
FIG. 15 is a top view thereof;
FIG. 16 is a bottom view thereof;
FIG. 17 is a perspective view of a remote control showing a third embodiment of my new design;
FIG. 18 is another perspective view thereof;
FIG. 19 is a front view thereof;
FIG. 20 is a rear view thereof;
FIG. 21 is a left side view thereof;
FIG. 22 is a right side view thereof;
FIG. 23 is a top view thereof; and,
FIG. 24 is a bottom view thereof.
